(57) CLAIM

An ornamental design for a footwear article, as shown and described.

DESCRIPTION

FIG. 1 is a front side view of a footwear article according to the present invention.

FIG. 2 is a rear side view of the footwear article of FIG. 1.

FIG. 3 is a right view of the footwear article of FIG. 1.

FIG. 4 is a left view of the footwear article of FIG. 1.

FIG. 5 is a top view of the footwear article of FIG. 1; and, FIG. 6 is a bottom view of the footwear article of FIG. 1. The broken lines, including the stitching applied to the upper and around the opening represent unclaimed subject matter and form no part of the claim. The stitch lines applied to the upper and around the opening of the footwear are for illustrative purposes only and form no part of the claimed design.

1 Claim, 5 Drawing Sheets

FIG. 2

FIG. 1

FIG. 3

FIG. 4

FIG. 5

FIG. 6
